FUEL OIL PUMP

Virgil A. Brunson, Grand Rapids, Mich., assignor to Blackmer Pump Company, Grand Rapids, Mich., a corporation of Michigan

Application May 28, 1954, Serial No. 433,043

1 Claim. (Cl. 103—221)

This invention relates to fuel oil pumps and its object is to provide means in such pumps for the flow of oil through the pump in reverse to the pumping direction of the flow.

The invention is particularly applicable to portable pumps used in the field to supply tractors, etc. In such use, the pump is usually used to pump fuel oil from a barrel which may be located on the ground or in a truck which transports it from place to place.

When the barrel is on the ground and the fuel tank is higher than the pump, after the fuel tank has been completely filled it is desirable to drain the fuel in the pump hose back into the barrel before removing the hose from the fuel tank to avoid spilling the contents of the hose upon the ground.

When the fuel barrel is on a truck and is higher than the fuel tank of the tractor, it is desirable to cause the fuel to flow by gravity or a siphoning action to avoid the labor of operating the pump and this invention provides means for the free flow of the fuel through the pump for this purpose.

The invention is frequently used with a pump operated by a hand lever which has means for being locked in a certain position and the invention provides means for moving the lever to the locking position after the fuel tank has been filled without pumping excess fuel through the hose.

The invention is not limited to the aforescribed uses nor to pumps for fuel oil but may be used on pumps for any free flowing liquid and for various purposes.

The invention provides various features of construction and arrangement hereafter more fully described, reference being had to the accompanying drawings in which:

Fig. 1 is a vertical elevation of a pump embodying the invention with parts in section.

Fig. 2 is a fragmentary vertical section of the same with parts moved to a different position.

Fig. 3 is a fragmentary transverse vertical section on the line 3—3 of Fig. 1.

Fig. 4 is a fragmentary sectional plan on the line 4—4 of Fig. 1.

Fig. 5 is an elevation, partly in section similar to Fig. 1 but showing a modified structure.

Fig. 6 is a fragmentary detail of the retaining spring of Fig. 3.

Fig. 7 is a fragmentary section of the by pass valve of Fig. 5, and

Fig. 8 shows the pump mounted in a fuel barrel.

Like numerals refer to like parts in all of the figures.

The pump has a main body 1 in which is a cylinder 2. A piston 3 is provided to reciprocate in the cylinder 2 and has a piston rod 4 extending outside the cylinder and is connected at 5 to an operating lever 6 which has a conventional handle 7.

The pump has a lower inlet chamber 8 to which is connected the inlet pipe 9 which is inserted into a fuel barrel 10, and an upper outlet chamber 11 connected to an

2

outlet pipe 12 to which is connected a flexible fuel hose 13.

The inner end of the cylinder 2 is in full communication with the interior of the body 1 which is separated from the chambers 8 and 11 by horizontal partitions 14 and 15 through which are the valve passages 16 and 17. Inlet and outlet valves 18 and 19 respectively operate to open or close the passages 16 and 17, each opening in the direction of flow of fuel through the pump and closing to prevent reverse flow.

In normal operation reciprocation of the piston 3 draws fuel oil into the pump body 1 through the inlet valve 19 and forces it out through the outlet valve 18 from where it passes through the pipe 12 and hose 13 to the desired receptacle. The operating lever 6 has pivotal connection at its lower end with the pump body 1 by a link 20 and above its connection 5 with the piston rod 4 it has an eye 21 which registers with a corresponding eye 22 on the pump body. A padlock hasp may be passed through the two eyes to prevent unauthorized operation of the pump.

In the style of pump shown in Figs. 1—4, a push rod 25 is located in the pump body 1 at the end of the cylinder 2 and is guided for vertical movement in the bases 26. A spring 27 normally thrusts the push rod downward. The upper end of the push rod is located below the outlet valve 18 and the lower end of the push rod is hook shaped to catch under the edge of the inlet valve 19.

A hand lever 28 located on the outside of the body 1 is mounted on a shaft 29 which passes into the interior of the body where it is provided with a radially projecting pin 30. One end of the pin 30 lies in a U bend 31 in the push rod and its other end engages a detent spring 32 having a pump therein.

In its normal lower position, where it is thrust by the spring 27 as shown in Fig. 1, the push rod 25 does not engage either of the valves 18 or 19 and permits them to open and close in the normal operation of the pump. But when the push rod is raised as in Fig. 2 by operation of the hand lever 28, the valves 18 and 19 are both raised to open position and held there by action of the detent spring 32.

When both valves are thus held open, the pump will not function and any liquid in the outlet pipe 12 or hose 13 above the pump will flow back through the pump to the barrel 10. Also when the valves 18 and 19 are both open the outlet of the hose is below the level of liquid in the barrel 10, a siphoning action occurs causing liquid to flow by gravity through the pump without operating the piston 3.

In the modified form of Fig. 5 the push rod 25 is not used but the liquid can be by-passed around the cylinder 2 and valves 18 and 19 through a passage 35 which is normally closed by a cock 36. In this form, when the cock 36 is open, operation of the piston 3 is ineffective and reverse flow of the fluid through the pump is accomplished substantially the same as though the valves 18 and 19 were held open and the siphoning action also occurs because the passage 35 permits a free flow from the inlet chamber 8 to the outlet chamber 11.

The invention is defined in the appended claims which are to be considered comprehensive of all forms coming within their scope.

65 I claim:

A pump comprising a body in which are a cylinder and a piston, an inlet passage opening to the bottom of said body, and an outlet passage opening to the top of said body both communicating with said cylinder, an inlet and an outlet valve in each of said passages, said piston normally acting to pump liquid through said valves from

said inlet passage through said outlet passage, and a single manually-operated-means acting to open both said valves, to permit a gravity reverse flow of liquid through said pump when said piston is at rest, said inlet and outlet passages and said cylinder being aligned and generally parallel with said bypass passage, so that said gravity flow will drain said cylinder and passages.
